Primary Examiner — John A Voytek(74) *Attorney, Agent, or Firm* — John Steckler Schwab(57) **CLAIM**

The ornamental design for a tire, as shown and described.

DESCRIPTION

FIG. 1 is a front right perspective view of a first embodiment of a tire showing our new design, the design repeated about the circumference of the first embodiment of the tire; FIG. 2 is a front elevation view thereof, the design repeated about the circumference of the first embodiment of the tire; FIG. 3 is a right elevation view thereof, it being understood that the left elevation view is identical thereto; FIG. 4 is a sectional view taken along line 4-4 in FIG. 2; FIG. 5 is a front right perspective view of a second embodiment of the tire showing our new design, the design repeated about the circumference of the second embodiment of the tire;

FIG. 6 is a front elevation view thereof, the design repeated about the circumference of the second embodiment of the tire; FIG. 7 is a right elevation view thereof, it being understood that the left elevation view is identical thereto; and,

FIG. 8 is a sectional view taken along line 8-8 in FIG. 6. Wherein dash-dot lines shown in FIG. 5-8 form no part of the claimed design and the dash-dot line shown in FIG. 5 and FIG. 7 represents a boundary line, radially inward from which form no part of the claimed design.
